UNITED STATES PATENT OFFICE.

GEORGE W. FARRIER, OF MILWAUKEE, WISCONSIN.

DESIGN FOR AN ANKLE MEMBER FOR ARTIFICIAL LEGS.

SPECIFICATION forming part of Design No. 33,773, dated December 25, 1900.

Application filed November 17, 1900. Serial No. 36,911. Term of patent 14 years.

To all whom it may concern:

Be it known that I, GEORGE W. FARRIER, a citizen of the United States, residing at Milwaukee, in the county of Milwaukee and State 5 of Wisconsin, have invented and produced a new and original Design for an Ankle Member for Artificial Legs, of which the following is a specification, reference being had to the accompanying drawings, forming a part thereof.

10 In said drawings, Figure 1 is a side view in elevation of an ankle member for artificial legs, showing my design. Fig. 2 is a rear view of the same. Fig. 3 is a view in cross-section taken through the center from front to rear 15 of an ankle member for artificial legs, showing my design. Fig. 4 is a top view of my design. Fig. 5 is a bottom view of an ankle member for artificial legs, showing my design.

The leading feature of my design for an 20 ankle member for artificial legs consists in the peculiar shape or formation of the same, which may be described as follows: The top of my design is substantially straight across between the points 11. From the point 1 in the 25 front side to a point 2 in the same side the design proceeds on a substantially straight line. The remainder of the design between the plane 11 and the plane 22 proceeds from the edge 11 to the line 22 on a curve, as shown 30 in Figs. 1, 2 and 3. Beginning with the line 22 and extending down to a line 33 the design proceeds outwardly on a straight line, forming an offset. From the line 33 to a point 4 in the center of the bottom edge of 35 my design the same proceeds on an irregular compound curve like unto the instep of a foot.

The back of the design from a point in line 33 extends down to a point 5 on a curve. From the point 5 to a point 6 in the bottom of my design the design is straight, while each 40 side of the same proceeds from the point 5 to the points 6 on a curve, as shown in Fig. 2. From the points 66 in the bottom line the design proceeds forward on straight lines to the points 7 and from the points 7 around on arcs 45 of circles to points 8, which are located in the sides of the design above the bottom line and form the bases of offsets 9 in the sides of the design which correspond to the ankle-bones in a foot. 50

The design is in the nature of a shell and proceeds from points A A in the inner upper edge to points B B in the inner lower edge on lines parallel with the lines in the outer surface. 55

The inner lower portion of the design is provided with a substantially L-shaped flange 11, extending from side to side of the design. Joining said flange and each side are cylindrically-formed projections 12 12, each provided near its inner side with a V-shaped flange 13.

Having thus described my invention, what I claim is—

The design for an ankle member for artificial 65 legs, substantially as shown and described.

Signed by me at Philadelphia, Pennsylvania, this 9th day of November, 1900.

GEORGE W. FARRIER.
